Des. 235,995
Patented July 22, 1975

235,995

ARTIFICIAL FISHING LURE

Robert K. Harris, Charlotte, N.C., assignor to
Ringley and Crockett, Inc.

Filed Sept. 24, 1973, Ser. No. 399,708

Term of patent 14 years

Int. Cl. D22—05

U.S. Cl. D22—27

Fig. 1

Fig. 2

Fig. 3

Fig. 4

Fig. 5

FIG. 1 is a plan view of an artificial fishing lure according to the design of the present invention;

FIG. 2 is a side elevation view of the lure of FIG. 1;

FIG. 3 is a bottom view of the lure of FIG. 1;

FIG. 4 is an end elevation as viewed from the left in FIG. 1; and

FIG. 5 is an end elevation as viewed from the right in FIG. 1.

I claim:

The ornamental design for an artificial fishing lure, as shown.
